UNITED STATES PATENT OFFICE

JACQUES L. DE MESQUITA, OF JERSEY CITY, NEW JERSEY

FIRE-ALARM BOX

Application filed August 29, 1929. Serial No. 329,126.

This invention relates to fire alarm systems and more particularly to alarm boxes such as are placed at predetermined signalling stations and from which persons may send in 5 alarms of fire. It is not uncommon, particularly in the large cities, for boys, mischievous persons or persons of defective mentality to signal false alarms and a careful check-up has shown that a large percentage of the 10 alarms received at fire headquarters are of this nature. When the false alarm is sent in the person signals the central station thus giving the alarm and immediately leaves the vicinity from which the alarm was given so 15 that it is extremely difficult to apprehend such persons who not infrequently remain at large through long periods and cause innumerable false alarms with incident expense to the fire department and their detention 20 from alarms which actually require urgent attention.

Furthermore, it is not uncommon for persons after giving a bona fide alarm to immediately leave the point from which the 25 alarm was given so that considerable time is lost by fire apparatus seeking the exact location of the fire when they reach the alarm box from which the alarm was given.

Experience has shown that, for the foregoing reasons and others which are well understood by persons familiar with fire department practice, it is highly desirable that the person sending in an alarm remain at the 30 point from which the alarm was given until the apparatus arrives at this point. The primary object of this invention is to compulsorily restrain such persons at such point even though they desire to immediately leave after giving the alarm. By this means, persons giving false alarms may be readily apprehended while persons turning in a bona fide alarm will be in position to properly direct the apparatus to the scene of the fire. 35

With the foregoing considerations in mind, the present invention consists in fire alarm box mechanism such as an appropriate call or signal box with which is associated means wherein a portion of the person sending in an alarm is grasped and retained in position, i. e., in effect, imprisoned against leaving the

box from which the alarm has been given until arrival of apparatus or some other person such as police officer having possession of a suitable key for effecting his release.

In the preferred manner of practically carrying out the invention, any suitable form of signal transmitting apparatus may be employed. Such apparatus generally embodies a handle adapted to be pulled down and when released returns to its normal position during which operation the alarm is given by mechanism well known to the art. The present invention consists in associating with such an apparatus restraining mechanism so positioned that when the hand of the person is placed in cooperative relation with the handle of the signal transmitting apparatus, said hand or arm is in cooperative relation with the restraining mechanism, the latter normally being in retracted position so as to permit of ready access to the handle. The signal transmitting mechanism is, however, operatively connected to the restraining mechanism so that when the hand draws down the handle to condition the alarm for operation, the restraining mechanism is actuated to grasp the wrist just back of the hand, as for example in a handcuff-like member, and to thus preclude withdrawal of the hand until the restraining mechanism is released by someone authorized to do so. With such an arrangement the person giving the alarm will not be able to leave the box after the alarm has been given but will be found at this point upon the arrival of the fire apparatus.

Features of the invention, other than those specified will be apparent from the herein-after detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a transverse section through apparatus embodying the present invention, this section being taken in the plane of the line 1—1 of Figure 2.

Figure 2 is a section on the line 2—2 of

Figure 1, showing certain parts in elevation in the interest of clearness.

In the apparatus shown in the accompanying drawings, 1 designates a housing in which is contained alarm transmitting apparatus of any appropriate conventional form, the details of which are immaterial so far as the present invention is concerned other than to note that such mechanism is adapted to be actuated for the purpose of giving alarm by downward pressure on the handle 2 which constitutes an element of the conventional apparatus. This apparatus is contained within a suitable casing or box 3 preferably provided at its front with a hinged door 4, the hinges being indicated at 5. The door is adapted to be normally locked in closed position by a suitable lock, not shown, and the keys for operating this lock are to be possessed by police officers and firemen so that under normal conditions, the box is locked closed against civilians. On the interior of the door 4 is mounted a partition 6 spaced from the door to provide an intermediate chamber 7 in which a greater portion of the restraining mechanism is housed. This restraining mechanism will now be described.

Pivotedly mounted on the bracket 8 on the partition 6 is a lever 9 one end of which overlies the handle 2 and carries the finger 10' adapted to bear on the upper face of the handle 2. To the other end of said lever is pivotally secured a bar 10 vertically slotted for a greater portion of its length as indicated at 11. Pivoted to the door 4 adjacent the lower end of the slotted bar 10 on the pivot 12 are two restraining jaws 14 and 15 having integral operating arms 16 and 17 respectively. These arms extend downwardly and in a divergent relation toward the opposite sides of the box as shown in Figure 1 and each arm carries an anchorage pin 18. Extending through the slot 11 of the bar 10 are two pivots 19 and 20. The upper pivot 19 forms the elbow pivot of the toggle embodying links 21 and 22 the terminal ends of which links are respectively pivotally secured to locking dogs 23 and 24 respectively. These locking dogs are mounted on pivots 25 supported by the door 4 and extend downwardly from these pivots whereby they are adapted to cooperate with serrated edges 26 and 27 formed on the restraining jaws 14 and 15. The toggle links 21 and 22 are secured to the dogs a short distance below the pivots 25, while the termini of another toggle embodying links 28 and 29 are pivotally secured to said locking dogs in further down position. The lower pivot 20 which extends through the slot 11 forms the pivot at the elbow of the lower toggle. The pivots between the termini of the lower toggle and the locking dogs are designated 30. A tension spring 31 extends between the pivot 30 of the dog 23 and the anchorage pin 18 of the arm 17 and

a spring 32 similarly extends from the pivot 30 of the dog 24 to the anchorage pin 18 of the operating arm 16. The parts are so arranged that the springs 31 and 32 will normally tend to force the restraining jaws 14 and 15 into the dot and dash line position shown in Figure 1.

The lower toggle, when its links are on dead centers or in alignment, will, however, hold the dogs 23 and 24 apart at their lower ends and thus cause tension members 33 connected between these dogs and the operating arms of the respective restraining jaws to hold said jaws in retracted position against the action of the said springs as indicated in full lines in Figure 2. It is not until the pivot 20 at the elbow of the lower toggle is lifted to "break" the toggle that the links thereof leave their relation of alignment, release the dogs for movement toward one another and thus permit the springs 31 and 32 to act upon the restraining jaws for the purpose of forcing them together into the dot and dash line position shown.

The restraining jaws, when in their retracted normal position indicated in full lines in Figure 1 are so shaped as to present between them a substantially circular opening 34 in the partition 6 and back of these jaws is formed a registering opening 35. The door 4 is also provided with an aligned opening 36 normally closed by small closure 37 which may be hinged as shown at 38.

By reference to Figure 2 it will be noted that the pull rod 39 is secured to the lever 9 adjacent the finger 10' which bears on the handle 2 and this pull rod hangs downwardly into the interior of the box to a point back of the openings 35 and 36. Thus, in order to send in an alarm, from apparatus such as designated, the person freely opens the small closure 37 which is left unlocked or with a key in the lock and is required to pass his hand through the opening 36, the opening 34 and opening 35 in order to grasp the pull rod 39, the depression of which causes the handle 2 to be forced downwardly and the alarm given. It will be noted, however, that when the rod 39 is pulled down, the lever 9 is tilted in a counter-clockwise direction thereby lifting the slotted bar 10. Since the pivot 20 at the elbow of the lower toggle is normally at the base of the slot 11, it will be apparent that this tilting of the lever will cause elevation of the elbow of the toggle so as to free restraint of the operating arms by the tension members 33 and permit the springs 31 and 32 to resiliently force the restraining jaws into their closed positions indicated in dot and dash lines, so that the arm of the hand which has sent in the alarm will be grasped by these restraining jaws at the wrist. During this operation, the lower ends of the dogs will follow the contour of the jaws and slide over the serrated edges 26 and 27 so as to preclude

any retrograde movement of the jaws during this operation and to function as a locking means to preclude the person who has given the alarm from forcing the jaws apart and withdrawing his hand. As the locking jaws 5 come together as indicated in dot and dash lines in Figure 1 during the operation just described, the upper toggle elbow falls into the dot and dash line position indicated in this 10 figure and it is also raised as shown toward the upper end of the slot 11.

After the parts have operated as stated, they will remain in these positions even though the pull rod 39 is lifted and the hand 15 which has caused the alarm to be given will be retained and locked in position so that it cannot be withdrawn. The person who has given the alarm will thus be caused to remain at the box until some authorized person releases him. This is accomplished when a fireman or other authorized person in possession of the key to the door 4 unlocks the door and opens it to reveal the releasing mechanism shown in Figure 2. This mechanism 20 consists merely in a knob 40 secured to the pivot 19 which projects through a slot 41 in the partition 6 carrying said knob. When the door 4 is opened, the knob may be readily grasped and pulled downwardly. This 25 operation causes the upper toggle to be straightened out to force the dogs 23 and 24 outwardly so that their lower ends are released from the serrated edges of the restraining jaws and tension simultaneously applied 30 to the tension members 33 to pull said jaws apart sufficiently to bring the links of the lower toggle into substantial alignment whereupon the apparatus is in re-set position 35 ready for the next alarm.

The apparatus which I have described is 40 infallible in its operation. It will effectively capture and hold the hand which gives the alarm and since the grip of the restraining jaws is spring impelled, the operation is 45 sufficiently resilient and yielding so as not to cause pain or injury of the wrist held within the grasp of said jaws.

The structure is relatively simple, economical to manufacture, and will effectively solve 50 the problems to which I have hereinbefore referred, arising out of false alarms and the failure of firemen to locate fires for which particular alarms are given.

The spring 9' normally holds the lever 9 55 in the position shown in Fig. 2 wherein the jaws are in open position and the parts ready for operation.

The foregoing detailed description deals with the invention in its preferred practical 60 form, but the invention is to be understood as fully commensurate with the appended claims.

Having thus fully described my invention, what I claim as new and desire to secure by 65 Letters Patent is:

1. In an assembly of the character described, a casing provided therein with a manually operable element, said casing having an opening through which a person's hand must be passed to operate said element, 70 a pair of jaws mounted on a stationary pivot in cooperative relation with the opening, said jaws having serrated edges and being provided with operating arms, a pair of locking dogs mounted on fixed pivots on opposite sides of the jaw pivot and adapted to coact with the serrated edges of the jaws, springs connecting said operating arms to the dogs and tending to move the jaws into closed position and also serving to maintain the dogs 80 in engagement with the said serrated edges, restraining members connecting the operating arms to the dogs to hold the jaws open when the dogs are forced apart, a setting toggle the terminals of which are secured to 85 the dogs to hold the jaws apart when the links of the toggle are in substantial alinement, and operative connections between said manually operable element and the elbow of said toggle to cause the toggle to be flexed 90 when said element is operated, whereby the dogs are permitted to move toward one another to allow the springs to close the jaws, said dogs following said serrated edges to lock the jaws in closed position, in combination with a resetting toggle also connected across the dogs and adapted to be manually operated to force the dogs apart and thereby return the jaws to open position and the links of the setting toggle to alined relation. 100

2. In an assembly of the character described, a casing provided therein with a manually operable element, said casing having an opening through which a person's hand must be passed to operate said element, a pair of jaws mounted on a stationary pivot in cooperative relation with the opening, said jaws having serrated edges and being provided with operating arms, a pair of locking dogs mounted on fixed pivots on opposite sides of the jaw pivot and adapted to coact with the serrated edges of the jaws, springs connecting said operating arms to the dogs and tending to move the jaws into closed position and also serving to maintain the dogs in engagement 115 with the said serrated edges, restraining members connecting the operating arms to the dogs to hold the jaws open when the dogs are forced apart, a setting toggle the terminals of which are secured to the dogs to hold the jaws apart when the links of the toggle are in substantial alinement, and operative connections between said manually operable element and the elbow of said toggle to cause the toggle to be flexed when said element is operated, whereby the dogs are permitted to move toward one another to allow the springs to close the jaws, said dogs following said serrated edges to lock the jaws in closed position. 120

3. In an assembly of the character described, a casing provided therein with a manually operable element, said casing having an opening through which a person's hand must be passed to operate said element, a pair of jaws mounted on a stationary pivot in cooperative relation with the opening, said jaws having serrated edges and being provided with operating arms, a pair of locking dogs mounted on fixed pivots on opposite sides of the jaw pivot and adapted to coact with the serrated edges of the jaws, springs acting on the operating arms and tending to move the jaws into closed position, restraining members connecting the operating arms to the dogs to hold the jaws open when the dogs are forced apart, a setting toggle the terminals of which are secured to the dogs to hold the jaws apart when the links of the toggle are in substantial alinement, and operative connections between said manually operable element and the elbow of said toggle to cause the toggle to be flexed when said element is operated, whereby the dogs are permitted to move toward one another to allow the springs to close the jaws, said dogs following said serrated edges to lock the jaws in closed position.
4. In an assembly of the character described, a casing provided therein with a manually operable element, said casing having an opening through which a person's hand must be passed to operate said element, a pair of levers of the first class mounted on a common stationary pivot and the work arms of which are shaped to form jaws cooperating with said opening, a pair of locking dogs mounted on fixed pivots on opposite sides of the jaw pivot and adapted to coact with the jaws to lock them in closed positions, means acting upon the levers and tending to move the jaws thereof into closed position, a setting toggle, restraining members operatively connecting the terminals of the toggle to the power arms of said levers and adapted to hold the levers with the jaws thereof in open position when the links of the toggle are in substantial alinement, and operative connections between said manually operable element, and the elbow of said toggle to cause the toggle to be flexed when said element is operated whereby the restraining members are relaxed to permit the jaws to close, said dogs serving to lock the jaws in closed position until said dogs are released.
5. In an assembly of the character described, a casing provided therein with a manually operable element, said casing having an opening through which a person's hand must be passed to operate said element, a pair of levers of the first class mounted on a common stationary pivot and the work arms of which are shaped to form jaws cooperating with said opening, a pair of locking dogs mounted on fixed pivots on opposite sides of the jaw pivot and adapted to coact with the jaws to lock them in closed positions, means acting upon the levers and tending to move the jaws thereof into closed position, a setting toggle, restraining members operatively connecting the terminals of the toggle to the power arms of said levers and adapted to hold the levers with the jaws thereof in open position when the links of the toggle are in substantial alinement, and operative connections between said manually operable element and the elbow of said toggle to cause the toggle to be flexed when said element is operated whereby the restraining members are relaxed to permit the jaws to close, said dogs serving to lock the jaws in closed position until said dogs are released; in combination with manually operable means for resetting the levers to a position wherein the jaws thereof are in opened condition.
- In testimony whereof I have signed the foregoing specification.
- JACQUES L. DE MESQUITA.
